UNITED STATES PATENT OFFICE.

JAMES M. HILLER, OF ALBANY, NEW YORK.

DESIGN FOR A COMBINED BROOM AND DUST-PAN HOLDER.

45,875.

Specification for Design.

Patented June 2, 1914.

Application filed October 28, 1913. Serial No. 797,910. Term of patent 7 years.

To all whom it may concern:

Be it known that I, JAMES M. HILLER, a citizen of the United States, residing at Albany, county of Albany, and State of New York, have invented a new, original, and ornamental Design for a Combined Broom and Dust-Pan Holder, of which the following is a specification, reference being had to the accompanying drawing, forming part thereof.

The figure is a perspective view of a combined broom and dust pan holder illustrating my new design.

I claim:

The ornamental design for combined broom and dust pan holder, as shown.

JAMES M. HILLER.

Witnesses:

Mrs. D. M. SUTHERLAND,
Mrs. C. A. DEARSTYNE.
